UNITED STATES PATENT OFFICE.

LOUIS B. PRAHAR, OF BROOKLYN, NEW YORK, ASSIGNOR TO HIMSELF AND
CHARLES S. SHEPARD, OF SAME PLACE.

DESIGN FOR A BAG, POCKET-BOOK, &c., FRAME.

SPECIFICATION forming part of Design No. 15,957, dated March 10, 1885.

Application filed January 24, 1885. Term of patent 7 years.

To all whom it may concern:

Be it known that I, LOUIS B. PRAHAR, of Brooklyn, in the county of Kings and State of New York, have invented and produced a new 5 and original Design for Bag, Pocket-Book, and Purse Frames, of which the following is a full, clear, and exact description.

Reference is to be had to the accompanying drawing, forming a part of this specification, 10 and which is a front elevation of a bag-frame illustrating my design.

The leading feature of my design consists in the scalloped projections upon the bars of the frame, the balls at the ends and center of the 15 said projections, and the angular finger in front of the center ball.

A B are the projections upon the top of the

frame C. The tops of the projections are scalloped or recessed, as shown in the drawing. At the ends and the center of the projections 20 A. B are balls D, and at the front of the center ball is an angular finger, E.

I claim—

The design for a bag, pocket-book, or purse frame herein shown and described, the same 25 consisting of the scalloped projections upon the bars of the frame, the balls at the ends and center of the said projections, and the angular finger in front of the center ball.

LOUIS B. PRAHAR.
